UNITED STATES PATENT OFFICE.

EMIL SCHNEIDER, OF HAMBURG, GERMANY.

CENTRIFUGAL PUMP, BLOWER, COMPRESSOR, AND THE LIKE.

1,126,300.

Specification of Letters Patent. Patented Jan. 26, 1915.

Application filed September 9, 1913. Serial No. 788,824.

To all whom it may concern:

Be it known that I, EMIL SCHNEIDER, a citizen of Switzerland, residing at Langerkamp 2, Hamburg, Germany, have invented 5 certain new and useful Improvements in Centrifugal Pumps, Blowers, Compressors, and the like, of which the following is a specification.

This invention relates to centrifugal 10 pumps, blowers, compressors or the like and has for its object to enable the individual disks or units for example in a set of centrifugal pumps of known type, to be connected or combined at will while in operation, a thing which is not possible at present. In this way a set of centrifugal pumps with the same number of revolutions and an approximately constant consumption of power would be able to overcome heads of 15 20 for instance 20 to 80 meters with a correspondingly modified output.

This is rendered possible according to the present invention by means of a new switch apparatus which allows various connections 25 or combinations of the disks or units to be effected.

This invention also comprises a novel construction of the casing of the pump, blower or compressor.

30 The accompanying drawings show the invention as applied to a four stage pump with four different connections.

Figure 1 is a side elevation of the pump. Fig. 2 is an end elevation of the same. Fig. 35 3 shows the switch apparatus partly in section and partly in elevation. Figs. 4, 5, 6 and 7 are transverse sections through the switch apparatus, namely through a set of inlet and discharge branches belonging to 40 one pump stage or unit showing different positions of the movable switch body.

The following combinations can be obtained with the above mentioned four connections. 1. Each disk or unit works independently. 2. Two disks are connected in series, so that two sets, each comprising two disks connected in series, work in parallel. 3. The disks are connected in series, while the fourth "stage" works independently. 50 Thus three stages work in parallel with one stage, that is to say in this arrangement there are two equal outputs or deliveries but different pressures. 4. All the four disks are connected in series.

55 The operation in the above named four cases is as follows:—In case 1 the four pump

disks draw water, each independently, through the branches g' , g^2 , g^3 , g^4 , and h' , h^2 , h^3 , h^4 of the switch apparatus (Figs. 3 and 5) the pipes q' , q^2 , q^3 , q^4 (Figs. 1, 2, 3 and 5) and through the pump branches d' , d^2 , d^3 , d^4 , each pump forcing the water through the pump branches e' , e^2 , e^3 , e^4 , pipes r' , r^2 , r^3 , r^4 , into the branches i' , i^2 , i^3 , i^4 of the switch apparatus from which it 60 flows through the branches l' , l^2 , l^3 , l^4 into the discharge piping. With this arrangement the pump delivers the maximum quantity of water that it is capable of delivering, while the pressure is equal to that produced 65 by one "stage." The water is guided through the switch apparatus in the same way for each pump, namely as shown in Fig. 5 in which the effective cross-section of the switch body is clearly indicated.

In case 2, the pump disks of the first and third stages draw water, each independently, through the branches g' and g^3 and h' and h^3 , pipes q' and q^3 and pump branches d' and d^3 , and discharge the said water 70 through the pump branches e' and e^3 pipes r' and r^3 into the branches i' and i^3 of the switch apparatus, in order to supply the water through the branches h' and h^3 and the connecting pipes s' and s^3 to the pump 75 branches f^2 and f^4 and thus to the disks two and four under pressure. The disks two and four discharge water through the pump branches e^2 and e^4 , pipes r^2 and r^4 and the switch apparatus branches i^2 and i^4 and l^2 and l^4 into the discharge piping. The quantity of water delivered with this connection or arrangement is half of that in the connection 1, while the pressure is double, as each two stages are in series. The water is 80 guided in the switch body in the planes of the branches g' and g^3 according to Fig. 4 and with respect to the branches g^2 and g^4 according to Fig. 6.

In case 3 the pump disks of the first and 85 fourth stage draw water, each independently, through the branches g' and g^4 , and h' and h^4 , pipes q' and q^4 and the pump branches d' and d^4 and force it through the pump branches e' and e^4 , pipes r' and r^4 into 90 the branches i' and i^4 of the switch apparatus. The water of the fourth stage is guided from the branch i^4 through the branch l^4 direct into the discharge piping. (Fig. 5) while the water of the first stage is 95 guided from the branch i' to the pump branch f^2 of the second stage, to the

disk of which it is supplied under pressure. The second disk conveys the water through the pump branch e^2 and pipe r^2 to the switch apparatus branch i^2 , from i^2 through 5 h^2 (Fig. 4) and s^2 to the pump branch f^2 . From here the water passes the third disk in order to flow from the same through e^3 , r^3 , i^3 to l^3 (Fig. 6) and further in the direction of pressure. The quantity delivered is here 10 half of that in the case 1, while the pressure at the branch l^3 is treble the individual "stage" pressure, and at the branch l^4 the pressure is the simple "stage" pressure. In the first place the water is guided on the 15 switch apparatus in the planes of the branches g^1 and g^2 as shown in Fig. 4, but subsequently the connection between the branches g^2 and h^2 is not utilized. In the switching plane g^3 the operative connections 20 are shown in Fig. 6. For the fourth pump stage, which works singly, Fig. 5 indicates the arrangement.

In the case of 4, the pump disk of the first stage draws water through the branches g^1 25 and h^1 , pipe q^1 and pump branch d^1 , and forces this water through the branch e^1 and the pipe r^1 toward the switch apparatus branch i^1 and thence to the branch h^1 (Fig. 4), then through the pipe s^1 toward f^1 and 30 the second disk, to which it is supplied under pressure. This disk increases the pressure and conveys the water through the pump branch e^2 , branches i^2 and h^2 (Fig. 7) and pipe s^2 , as well as the pump branch 35 f^2 , to the third disk. After further increase of pressure in the third stage the water is forced by that disk through the pump branch e^3 , pipe r^3 to the branches i^3 and h^3 (Fig. 7) and then through the pipe 40 s^3 toward the branch f^4 and the fourth disk. The pressure in the fourth stage increases in the same manner, whereupon the water flows through the pump e^4 , pipe r^4 , branches i^4 and h^4 (Fig. 6) into the discharge piping. 45 The quantity delivered in this connection is a quarter of that delivered in the arrangement 1, while the pressure is equal to a quadruple "stage" pressure. The water is guided in switch apparatus in the plane g^4 according to Fig. 4, planes g^2 and g^3 according to Fig. 4, but without the use of 50 the connection between the branches g^2 and g^3 and h^2 and h^3 as well as in the switch plane g^4 of the last stage according to 55 Fig. 6.

For obtaining one of the four connections, the switch body or piston p is longitudinally moved manipulating the hand wheel p^2 which is operatively connected to the rod p' of the piston p . The cross-sections marked m , n , o , t , corresponding to Figs. 4, 5 6 and 7 become consecutively operative. As the connections can be obtained with a single switch body, the different positions can be obtained without loss of time 60 65

and in an absolutely reliable manner by one attendant, by means of a single control or switch part. The switch part is provided with the same number of "connection planes" provided with branches and groups 70 of guide cross sections on the switch body, as there are pump stages. For each switch plane are required as many switch cross sections m , n , o , t , or branch connecting members, as there are connections to be 75 made.

The invention can be used also for rotary stage pumps, such as blowers, compressors, etc. Moreover, if desired, the whole connection device can be built in one with the 80 pump, the pipes being replaced by conduits. The pump or blower or compressor casings differ in construction from those hitherto known, by each stage being provided with one discharge branch e and all, except the 85 first, with two suction branches d and f or corresponding conduits.

What I claim is:—

1. In a centrifugal pump the combination of a plurality of pump units each having a branch for a suction pipe connection and a branch for a delivery pipe connection and each except the first or endmost having also a second branch for a suction pipe connection, a cylindrical casing having a 90 plurality of groups of branches for pipe connections disposed along it, a single piston longitudinally movable within the casing and comprising a plurality of groups of branch connecting members each of which groups is positioned in the casing so as to coöperate with and control the flow of fluid through one of the groups of branches, means for moving the piston, and pipes connecting the pump branches and 95 the casing branches as set forth.

2. In a centrifugal pump the combination of a plurality of pump units each having a branch for a suction pipe connection and a branch for a delivery pipe connection 110 and each except the first or endmost having also a second branch for a suction pipe connection, a cylindrical casing having a plurality of groups of branches for pipe connections disposed along it all the branches in any one group being positioned so that they lie in a plane normal to the axis of the cylinder, a single piston longitudinally movable within the casing and comprising a plurality of groups of branch connecting members each member of each group operating when positioned in the plane of a group of casing branches to control and direct the flow of fluid through that group of branches, means for moving the piston, and pipes connecting the pump branches and the casing branches as set forth. 115 120 125

3. In a centrifugal pump the combination of a plurality of pump units each hav- 130

ing a branch for a suction pipe connection and a branch for a delivery pipe connection and each except the first or endmost having also a second branch for a suction pipe connection, a cylindrical casing having a plurality of groups of branches for pipe connections disposed along it all the branches in any one group being positioned so that they lie in a plane normal to the axis of the cylinder, a single piston longitudinally movable within the casing and comprising a plurality of groups of branch connecting members, the members in the several groups being individually so formed and relatively so placed on the whole piston that each member of each group when positioned in

the plane of a group of casing branches operates to control and direct the flow of fluid through that group of branches and so effect a coupling of the pump units in 20 various ways, means for moving the piston, and pipes connecting the pump branches and the casing branches as set forth.

In testimony whereof I have hereunto signed my name this 25th day of August 25 1913 in the presence of two subscribing witnesses.
